UNITED STATES PATENT OFFICE.

ROBERT L. DENNISON, OF KANSAS CITY, MISSOURI.

KILN.

1,141,619.

Specification of Letters Patent.

Patented June 1, 1915.

Application filed July 21, 1913. Serial No. 780,261.

To all whom it may concern:

Be it known that I, ROBERT L. DENNISON, a citizen of the United States, residing at Kansas City, in the county of Jackson and State of Missouri, have invented certain new and useful Improvements in Kilns, of which the following is a specification.

My invention relates to improvements in brick kilns, and more particularly to means for supplying the furnaces thereof with air, to the end that economy in the consumption of fuel and more thorough combustion of gases arising from such consumption is attained.

15 In order that the invention may be fully understood, reference will now be made to the accompanying drawings, in which:

Figure 1 is a sectional plan view of a kiln embodying the invention. Fig. 2 is a broken 20 vertical section on line II of Fig. 1. Fig. 3 is a broken vertical section on line III—III of Fig. 2. Fig. 4 is a detail perspective of an air controlling means constituting a feature of the invention.

25 1 designates a kiln having a series of furnaces 2 arranged at each longitudinal side thereof. Each furnace is divided into a combustion-chamber 3 and an ash-pit 4 by a grate 5, of any ordinary or preferred 30 form. Access is had to the combustion-chamber 3 to supply the grates with fuel, through an opening 6 normally closed by a door 7, and access is had to the ash-pit 4 through an opening 8 normally closed by 35 a close-fitting door 9. The combustion-chamber 3 communicates with the interior of the kiln through an opening 10, the lower side of which is formed by a bridge-wall 11.

12 designates an air receptacle laid in the 40 bridge-wall 11 during the construction of the same, just beneath the grate 5. Said receptacle is substantially T-shaped in plan view, and has an inlet 13 controlled by a valve 14, hinged at its upper edge to the receptacle 12. The rear upper portion of the 45 receptacle 12 is provided with a plurality of upwardly and forwardly inclined nozzles 15, which discharge into a cavity 16 in the upper forward portion of the bridge-wall 11, see Fig. 1. Cavity 16 has a ledge 17 which overlaps the discharge ends of the nozzles 15 and thus excludes dust, cinders, and other foreign matter therefrom.

50 Valve 14 is controlled by a hinged-rod 18 extending back through the front wall of the furnace and provided with a handle 19,

so that an operator may control said valve from a point in front of the furnace. Rod 18 is of such weight and runs through the front casting 20 of the furnace with sufficient friction to maintain the valve 14 either 60 completely or partially open, so that the quantity of air entering the inlet 13 may be controlled to a nicety.

21 designates branch ducts extending beneath the furnaces at the sides of the kiln, as shown on Fig. 1. Each duct 21 communicates with each furnace on its respective side of the kiln through a port 22 in a plate 23 covering the duct the width of the fur- 65 nace.

The passage of air through port 22 is controlled by a valve 24, slidably-mounted upon the plate 23 which is held in place by the furnace walls and has two guides 25 to 70 maintain the valve in proper position when it is slid backward or forward to cover or uncover its respective port 22. Valve 24 like the valve 14, is controlled from the exterior of the furnace by a rod 26 extending 75 through the front wall of the furnace and provided at its outer end with a handle 27. The branch ducts 21 communicate with a main duct 28, which may receive its supply of air from any suitable source, such, 80 for instance as a fan or blower. The main duct 28 is of such cross sectional area and length as to supply a series of kilns. In order that the flow of air through the branch ducts may be independently controlled so 85 that each will receive only the desired amount of air from the main duct 28, I provide said branch ducts with individual valves 29.

In practice, when the furnaces are in operation, they are supplied entirely with air flowing through the ports 22, which air enters the ash-pits and passes upward through the receptacles 12 and the grates 5. Should it be found that air passing through 95 the grates and the burning fuel thereon, fails to result in complete combustion of the carbon and gases arising from such combustion, the valve 14 is opened to allow air to enter the receptacle 12 and be distributed through the nozzles 15 at a point adjacent the bridge-wall 11, where it combines with said gases while the same are in their most highly heated state, and furnishes the necessary oxygen to insure thorough 100 combustion of said gases and the carbon mixed therewith. The extent to which 105

each valve 14 should be opened is readily determined by an experienced operator on looking into the furnace through the usual peep-holes, to ascertain the condition of the fire. Should the source of air supply to the main duct 28 become disabled and thus fail to provide the fires in the furnaces with the necessary amount of air to insure complete combustion, the ash-pit doors 9 are opened 10 to allow the necessary flow of air into the furnaces through the openings 8.

While I have shown and described the preferred form of my invention, I reserve the right to make such modifications as 15 properly fall within the spirit and scope of the claim.

Having thus described my invention, what I claim and desire to secure by Letters Patent is:

20 A kiln of the class described comprising a furnace including a combustion chamber having a bridge wall, said bridge wall having a longitudinal cavity formed therein, an

air receptacle embedded in the bridge wall and disposed below the cavity, a plurality 25 of inclined nozzles leading from the air receptacle to the bottom of the cavity, the top wall of said cavity being disposed directly above the upper open ends of the nozzles, said air receptacle having a branch extending 30 into the ash pit of the furnace, a damper hingedly connected to said extended end, a rod slidably and frictionally engaged in the outer wall of the furnace, a link pivotally connecting said damper and rod, and 35 a handle formed upon the outer end of the rod, said rod being held in its adjusted position by its frictional engagement with the furnace wall.

In testimony whereof I affix my signature, 40 in the presence of two witnesses.

ROBERT L. DENNISON.
